UNITED STATES PATENT OFFICE.

WILLIAM LAWRENCE, OF FOLKESTONE, ENGLAND.

TOY FOR GAMES.

SPECIFICATION forming part of Letters Patent No. 510,038, dated December 5, 1893.

Application filed May 22, 1893. Serial No. 475,143. (No model.)

To all whom it may concern:

Be it known that I, WILLIAM LAWRENCE, a subject of the Queen of Great Britain, and a resident of Folkestone, in the county of Kent, England, have invented certain new and useful Improvements in Toys for Games, of which the following is a full, clear, and exact specification.

This invention relates to an improved toy for use when playing a game of bat and ball and the same is constructed in the following manner, reference being had to the accompanying drawings.

Figure 1 shows a side elevation of my invention; Fig. 2 plan of same.

a is a block of wood, shaped as shown, having a handle b at its taper end and an indentation c at its enlarged end. At the extremity of this piece of wood is secured a rim of wire d to which is connected a bag or net e.

The toy is used as follows: The ball is placed in the indentation c and the player

throws the ball to his opponent, who has a similar device to that shown, who endeavors to catch the ball in the bag or net e, after which he similarly returns the ball and so on.

What I claim, and desire to secure by Letters Patent, is—

In toys a block of wood one end of which is tapered to a handle, the other end is enlarged and provided with an indentation c, a rod or bar carrying a net e said rod being attached to a block of wood substantially as described and shown.

In testimony that I claim the foregoing I have hereunto set my hand this 28th day of April, 1893.

WILLIAM LAWRENCE.
